UNITED STATES PATENT OFFICE.

HARRY J. MOREY, OF SYRACUSE, NEW YORK, ASSIGNOR TO PASS & SEYMOUR, INC., OF SOLVAY, NEW YORK, A CORPORATION OF NEW YORK.

SIGN-RECEPTACLE.

1,183,101.

Specification of Letters Patent. Patented May 16, 1916.

Application filed November 28, 1913. Serial No. 303,590.

To all whom it may concern:

Be it known that I, HARRY J. MOREY, a citizen of the United States, residing at Syracuse, Onondaga county, New York, have invented certain new and useful Improvements in Sign-Receiptacles, of which the following is a specification.

This invention relates to electrical receptacles for incandescent lamps and the like, and more particularly to a receptacle for use on signs, etc., being provided with novel means for locking it against rotation relatively to the sign plate on which it is mounted.

15 The principal object of the invention is to eliminate unnecessary fastening devices and provide a part of the receptacle with a series of angular recesses or notches adapted to be engaged by an inwardly depressed lip 20 at the opening of the sign plate and lock the receptacle in any one of many positions rotarly.

25 The above and other objects, and the novel features of the invention will be apparent from the following description, taken in connection with the drawings, in which,—

30 Figure 1 is a perspective view of the parts of the receptacle and the sign plate when separated. Fig. 2 is a top plan view of the base of the receptacle. Fig. 3 is a bottom plan view of the receptacle, and Fig. 4 is a vertical cross sectional view taken in a plane perpendicular to the sign plate.

35 Referring to the drawing, the receptacle consists of a base of porcelain or other insulating material comprising the disk portion 10 and an annular flange portion 11 rising at the periphery of the disk portion 10. Rising at the inner edge of the annular 40 flange 11 is a lip 12 which is adapted to extend through the opening 13 in the metal sign plate 14. The inner wall of the lip 12 is continuous with the inner wall of the flange 11 and forms a cavity 15 in the bottom of which the lamp terminals are secured.

45 The lamp terminals comprise the usual screw socket shell 16 attached to the disk-like portion 10 by the conducting screw 161 and a center terminal spring 17 secured in place by the conducting screw 20. The socket shell 16 is electrically connected to the terminal post 18 by one of the screws 161 and by the plate 181 and the center

55 spring contact 17 is electrically connected to the terminal post 19 through the screw 20 and a suitable connection plate 21.

60 The bottom face of the disk-like portion 10 of the base of the receptacle has two parallel grooves 22 and 23 through which the passing wires of the electrical circuit extend, the terminal posts 18 and 19 being disposed in said groove below the bottom face of the base and adapted to clamp the circuit wires to the plates 181 and 21, respectively. 65

70 The lip 12 extends outwardly beyond the end of the socket shell 16 and has exterior threads 25 adapted to receive the interior threads 26 on the annular metal securing ring 27 by means of which the receptacle 75 is rigidly attached to the under side of the sign plate 14. A gasket 28 fits between the overlapping flange 29 of the attaching ring 27 and the edge of the opening 13 in the sign plate.

75 Spaced from the annular lip 12 by the groove 30 and rising at the outer edge of the annular portion 11 there is an annular rim or flange 31. The rim 31 extends for a considerable distance above the disk portion 10 80 and flange portion 11, surrounding the socket shell 16 and lip 12 and extends a slight distance above the shell 16.

85 The upper edge of the rim flange 31 is notched throughout its entire length. Angular radially disposed notches 32 alternate with projections 33 and form the upper edge of the rim flange 31. The top edges of the projections 33 engage the under side of the sign plate 14. A depressed lip or lug 34, 90 substantially the width of a notch, is struck inwardly from the plate 14 at the margin of the opening 13 and has angular cut metal edges adapted to fit any one of the notches 32 at the upper edge of the rim flange 31 to 95 lock the receptacle in any one of many positions rotarly, each one of the notches 32 having angular shoulders at opposite sides thereof against which the angular edge of the lip 34 engages.

100 By providing the receptacle with an annular row of notches at the edge which engages the under side of the sign plate 14 it is possible by simply depressing a narrow lip at the margin of the opening in the sign plate, to lock the receptacle in a predetermined position so that it will not work around and break connections or cause other

damage. It is not intended to limit the construction to the particular type of receptacle herein disclosed, as it will be obvious that the invention may be applied to various forms of receptacles without departing from the spirit of the invention.

Having thus fully described my invention, what I claim is:

1. A receptacle capable of use with a sign plate provided with an aperture and a lug on the inner side of the plate near the edge of said aperture, said receptacle comprising a circular part which engages the inner side of the sign plate, said circular part having a series of projections and notches arranged alternately thereon at the edge thereof which engages the inner face of the sign plate, said series of projections and notches extending throughout the entire length of the plate-engaging edge of said circular part, any one of said notches being capable of fitting said lug to lock the receptacle in any one of many positions rotarily, whereby a choice of many angular positions of the line terminals of said receptacle is afforded.
2. The combination with a sign plate having an opening therethrough and a lug at the inner side thereof near the opening, of a receptacle adapted to be locked to the plate in any one of many positions rotarily, and means for fastening the receptacle to the sign plate, said receptacle having a circular row of notches, any one of which is adapted to take said lug and lock the receptacle in any one of many positions rotarily, whereby a choice of many angular positions

of the line terminals of said receptacle is afforded.

3. A receptacle capable of use with a sign plate having an aperture therein and a lug at the edge of said aperture, said receptacle comprising a body of insulating material having an inner cylindrical flange and a second shorter cylindrical flange surrounding and spaced from said inner flange and having an edge capable of engaging the rear face of the sign plate, means capable of engaging said inner flange to secure the receptacle in place on the sign plate, said shorter flange having transverse notches throughout its entire plate-engaging edge, any one of said notches being capable of fitting the lug on the sign plate to lock the receptacle in any one of many positions rotarily.

4. The combination of a sheet of metal having an aperture therein and a lug adjacent the margin of said aperture, said lug consisting of an inwardly struck portion of the sheet, an electric lamp receptacle adapted to be locked to said sheet in any one of many positions rotarily, and means for fastening the receptacle to the sheet of metal, said receptacle having a circular row of notches, any one of which is adapted to fit said lug and lock the receptacle in any one of many positions rotarily.

In testimony whereof I affix my signature in presence of two witnesses.

HARRY J. MOREY.
